United States Patent Office

Des. 201,081
Patented May 11, 1965

201,081

PERFORATED CARD READER

Alfred W. Stewart, New Paltz, N.Y., assignor to A. W. Stewart Associates, Inc., Kingston, N.Y., a corporation of New York

Filed Jan. 16, 1964, Ser. No. 78,217

Term of patent 14 years

(Cl. D26—14)

FIG. 1

FIG. 2

FIG. 3

FIG. 4

FIG. 5

FIG. 1 is a front isometric view of a perforated card reader showing my new design;

FIG. 2 is an elevational view of the side opposite that shown in FIG. 1;

FIG. 3 is a top plan view thereof;

FIG. 4 is a rear elevational view thereof; and

FIG. 5 is a bottom view thereof.

The essential features of my design are shown in full lines in the drawings.

I claim:

The ornamental design for a perforated card reader, as shown and described.
